HARMON E LINDBLADH, OF BROOKLINE, MASSACHUSETTS, ASSIGNOR TO THE LINDBLADH CORPORATION, A CORPORATION OF MASSACHUSETTS.

RULING APPARATUS.

Application filed August 3, 1923. Serial No. 655,536.

In my application Serial No. 501,227, filed September 17, 1921, is disclosed a duplex ruling machine consisting of two ruling apparatus arranged to operate successively upon sheets and produce upon them, by sets of pens or other ruling devices, corresponding sets of intersecting lines. With each set of pens is an associated controlling device, in the form of a gate, by which the sheets are released at predetermined times, to be acted upon by the pens. In these ruling apparatus, the pens and gates are movable, and are provided in each apparatus with actuating mechanism, preferably furnished by cams rotatable with a shaft, which causes the pens and gate to be raised and lowered in timed relation, to vary, in any desired manner, the terminal-points of the lines ruled. Between the apparatus the sheets pass through a transfer mechanism, which receives and delivers them in time with the operation of the pens and gates by the cams. To assure the correct striking of the pens, or their removal from and return to the work at chosen points, the cam-shafts of the two apparatus and the transfer mechanism, but especially the former, must be actuated in synchronism. In the previously-mentioned machine, this action is attained by applying power from a suitable source to the cam-shaft of the first apparatus, gearing this to the transfer mechanism, and again gearing the latter to the cam-shaft of the second ruling apparatus. While such an operation is entirely correct in theory, the long train of gearing between the power-source and the last ruling apparatus tends to introduce difficulties. There is a cumulative backlash in the multiple-gearing elements, which may cause difficulty in the timing of the apparatus, for which it is troublesome to make allowance, particularly as it is variable. Moreover, exact synchronism may further be interfered with by torsion in the successive shafting, this shafting being so situated that it cannot conveniently be made sufficiently rigid. It is an object of this invention to eliminate this lost motion from the various mechanisms, and to provide a system in which the synchronism shall, for all practical purposes, be perfect.

To feed sheets from a pile, to be acted upon one by one by a ruling apparatus, it has been customary to drive the feeding elements from the sheet-conveying system of the ruling apparatus. When, in the control of a ruling apparatus to adapt it to operate upon sheets of different lengths, its timing has been altered by change-speed gearing between the conveying system and cam-shaft, as will be understood by reference to Patent No. 1,242,823, Oct. 9, 1917, in my name, it has been necessary to interpose a similar change-speed gearing between the conveying system of the ruling apparatus and the feeding mechanism, so that a sheet shall be delivered for each operation of such ruling apparatus. This compels the inclusion in the feeder equipment of an expensive set of some twenty-five gears, and throws upon the operator the burden of making a double gear-shift when the sheet-dimensions change. In addition to this, in a duplex ruling machine of the character of that herein described, since the alteration in the sheet-size is in part provided for by a change in the rate of travel of the conveying system at the first apparatus, the gearing change between the conveying system and the feeding mechanism ceases to be identical with that between said system and the cam-shaft, but assumes a complicated ratio, troublesome to compute and difficult for the operator to follow. This invention furnishes a connection between the ruling apparatus and feeding mechanism which entirely does away with change-speed gearing.

Much paper which must be ruled is in a warped or uneven condition, so that, in passing beneath the pens, the surface with which they contact is at different heights, and the points of striking are rendered inexact. One of the objects of my invention is to maintain the surface of the work in proximity to the pens at a constant level, so that the lines produced by said pens will agree with the setting of their actuating means.

One of the several forms which my invention may assume is illustrated in the accompanying drawings, Figure 1 showing an elevation of a duplex ruling machine, looking at the side of the first apparatus, and including the feeding mechanism, parts being broken away and omitted; Fig. 2, an end elevation of the first ruling apparatus and a

side elevation of the second, together with the connecting transfer mechanism, here parts also being broken and omitted: and Fig. 3, a perspective view of the pressure-fingers associated with the pens.

Like characters designate corresponding parts throughout the figures of the drawings.

The duplex machine shown is made up of 10 a ruling apparatus A, which first acts upon the sheets, and a second apparatus B extending generally at right angles to the apparatus A and arranged to produce lines intersecting those formed thereby. Transfer 15 mechanism C changes the direction of travel of the sheets, so that, after leaving the apparatus A, they properly enter apparatus B. The structural details of the ruling apparatus and transfer mechanism in no way concern 20 the present invention, so nothing more than a brief outline of the elements will be given. In a frame 10 of the apparatus A is mounted for independent movement, as in Patent No. 1,242,823, a set of pens 12 operating 25 over a sheet-conveying cloth or endless web 14, receiving its motion from the lower of a pair of feed-rolls 16, 16 journaled horizontally in the rear portion of the frame. These rolls receive the sheets fed between 30 them, and advance them to the conveyor which carries them beneath the pens. The pens are raised from and returned into contact with the sheets upon the conveyor by actuating mechanism including series 17 of 35 levers operated by cams 18 supported by a shaft 20 rotatable upon standards rising from the opposite sides of the frame 10 just in advance of the rolls 16. Operating to the rear of the pens, here shown as beneath 40 the cam-shaft, is an oscillatory gate 22, which alternately stops and releases the sheets as they are brought to it by the conveyor, determining the time at which they are delivered to the pens. This gate is 45 preferably operated by a lever 19 under the influence of a cam 21 upon the shaft 20. As to the just-described elements, the ruling apparatus B may be identical with A.

The transfer mechanism C may include 50 conveyor-tapes 24 receiving the ruled sheets from the conveying system of the apparatus A at its lower forward portion, and bringing them under the influence of revoluble transfer-sectors 26 carried upon a shaft 28 55 journaled at one side of the frame 10 of apparatus A. The sectors thrust the sheets upon upwardly inclined tapes 30 extending at right angles to the tapes 24 and traveling in a frame 32. This frame connects the 60 main frames 10, 10 of apparatus A and B, and is so located that the tapes 30 deliver the sheets to the rolls 16, 16 of the latter.

Mounted to turn in bearings in the frame 65 of apparatus A is a horizontal shaft 40 connected to a source of power, as an electric

motor 42, by transmission-gearing 44 governed by a shifting device 46. The purpose of this gearing 44 is to change the rate of operation of the entire duplex machine so that it will act upon a greater or less number of sheets in a given time. Mounted to rotate in the frame of apparatus B and lying in the same horizontal plane as the shaft 40, to which it is joined by equal-ratio bevel-gearing 48, is a shaft 50. The shaft 40 is 70 connected directly to the cam-shaft 20 of apparatus A by change-speed gearing 52, while shaft 50 has like connections to the cam-shaft of apparatus B through change-speed gearing 54. Both the shafts 40 and 50 carry 75 no operating elements, acting to supply power only, and being so located upon the frame that the bearings may be ample and the shaft of any suitable size to resist torsion under the maximum load. Moreover, from 80 this system of shafting, which is unvarying in action throughout because of the single bevel-gear connection at 48, motion is imparted to the two cam-shafts of the ruling apparatus A and B through short trains 85 of inflexible gearing, wholly independent of each other, so there is none of the uncertainty of action produced by chain-drive and passing from one train of gearing to another. There results unvarying synchronism between the cam-shafts of the two apparatus, with ability to so set the actuating mechanism of the pens that those of the second apparatus B will strike precisely with 90 reference to the lines produced by the apparatus A. The change-speed gearing 52 and 54 gives simple and effective means for maintaining this synchronism when changes are made for ruling sheets of different maximum dimensions. That is, assuming that 95 cross-ruling, or that extending transversely of the sheets, is to be done upon the apparatus A, and down-ruling, or that lying longitudinally of the sheets, upon the apparatus B, if a sheet of a different length is to 100 be operated upon, this will be provided for by a suitable shift in the gearing 54. Then, upon making the same change in the gearing 52, there will be a maintenance of synchronism, which permits accurate setting of the 105 actuating mechanisms at the two apparatus to insure precision in the relation between the lines ruled by the two sets of pens.

It is to be noted, however, that with adjustments of this character, when the sheets are other than square, with the transverse dimension less than the longitudinal, these would be so released by the gates that they would be more widely spaced in the apparatus A than in apparatus B. For example, if the sheets were 28" x 28" and the gearing 52 and 54 were set to cause the gates 22 to release these to give the desired spacing of about a half an inch between the successive sheets, then if a sheet 28" x 17" were to be 110

operated upon, the space between the sheets in the apparatus A would become eleven and a half inches. This would be inefficient in slowing the operation of the machine, 5 and would cause the pens to drag upon the conveyor over the spaces, wasting ink and daubing the sheets. Therefore, while the feed-rolls 16 and the conveyor-cloth driven thereby of apparatus B are operated 10 through constant-speed gearing 56, these in apparatus A receive their travel from change-speed gearing 58. By a suitable shift in the gear-ratio, the travel of the sheets through the first apparatus may be 15 slowed to any desired extent, and they may be brought, upon their release by the gate, to within the desired half-inch of each other. The feed-roll-gearing 56 and 58, it will be seen, is driven directly from the power- 20 shafts 40 and 50, and while the consequent freedom from the effect of backlash and torsion does not improve the accuracy of striking of the pens, since this is obtained from the perfectly synchronized cam-shafts 25 20, 20, it gives an exceedingly compact and efficient system of connections which introduces practically no maintenance cost.

To synchronize the rotation of the shaft of sectors 26 with the cam-shafts, so such 30 sectors will unfailingly deliver a sheet for each operation of the pens of apparatus B, it is effectively driven from the cam-shaft of apparatus A through bevel-gearing 60 acting upon a vertical shaft 62 rotatable in 35 the frame of this apparatus, and which, in turn, communicates motion by bevel-gearing 64 to a horizontal shaft 66 extending longitudinally of this frame. Sprocket-gearing 68, including a short chain, joins the shaft 40 66 to the sector-shaft. Here the drive cannot be from the power-shafts 40 and 50, on account of the necessary gear-changes between said shafts and the cam-shafts, which would destroy the constant time-relation 45 between the cam-shafts and sector-shaft. The minor irregularities of action of the sectors introduced by the backlash of the longer chain of gearing do not affect the 50 perfection of the striking of the pens at apparatus B, it being only necessary that the sheet reach the gate 22 of such apparatus in time for retention and release for each turn of the cam-shaft.

Delivering to the feed-rolls 16, 16 and co- 55 operating conveyor 14 of the ruling apparatus A is a feeding mechanism D, the function of which is to supply sheets successively to receive the action of the pens 12 of apparatus A. This feeding mechanism 60 must be so timed as to place under the control of the gate 22 a sheet for each gate-operation and consequently each group of pen-movements. The feeder is shown as of 65 the type disclosed in my Patent No. 1,258,026, March 5, 1918, so is illustrated only

in its more essential particulars. A table 70 is arranged to support a pile of sheets S, raised and lowered automatically to maintain the upper sheet of the pile at the level from which delivery is to be effected. Co- 70 operating with the table is a reciprocating presser-foot or member 72 for temporarily retaining the pile of sheets when the upper one is being acted upon by a revoluble device 74, which successively moves over one 75 another or fans out and then advances or feeds said sheets. Upon the feeding action of the device 74, it delivers the sheets successively to a conveyor 76, which may be furnished by endless tapes, these, in turn, 80 advancing said sheets to the feeding rolls 16, 16 and the cloth 14 of ruling apparatus A. To maintain synchronism between the feeder and ruling apparatus, the device 74 must effect delivery for each operation of 85 the cam-shaft 20. The conveyor 76, however, preferably travels at substantially the same rate as the feeding elements 16 and 14 of apparatus A, so that the uniform advance of the sheets at the rate which gives 90 the proper spacing during the ruling operation is obtained. This I accomplish by joining the delivery device 74, and the presser-foot 72 which operates in timed relation with it, to the cam-shaft 20 of the apparatus 95 A by equal-ratio gearing. A suitable arrangement is furnished by sprocket-gearing 78 connecting the cam-shaft 20 to an idler shaft 80, sprocket-gearing 82 joining this shaft 80 to a shaft 84 of the feeder. The 100 devices 72 and 74 are operated from the shaft 84 through sprocket-gearing 86. Therefore, the desired constant timing between the delivery device of the feeder and the cam-shaft of apparatus A is maintained, 105 irrespective of changes in the gearing at the latter and without alteration of the feeder-gearing. The conveyor 76 is shown as connected directly to the lower feed-roll 16, preferably by equal-ratio sprocket-gearing 110 88. As a result of this, whenever the travel of the cloth 14 is altered by a shift in the gearing 58, the advance of the feeder-tapes is similarly changed to give unvarying advance of the sheets from the pile in the 115 feeder to the gate and beneath the pens of ruling apparatus A.

When the sheets fed reach the pens 12 of the ruling apparatus, they may have portions which, due to moisture or other causes, 120 are buckled, so that they are elevated above the general plane of the sheets. Obviously, these higher indeterminate portions will contact with the pens before the points for which the machine is set, and thus destroy the true striking relation. This I overcome by providing pressure members, in the form of spring-fingers 90 and 92. These fingers are associated in sets with each of the sets 125 of pens, each set of fingers being mounted 130

upon a support, which is illustrated as a cylindrical rod 94 fixed at its ends in brackets rising from the sides of the frame 10. Each finger is shown as carried by a holder 96 having a portion surrounding the rod and a laterally projecting portion divided at 98. The finger may be inserted in the divided portion, and clamped in place by a set-screw 100. A set-screw 102, threaded 10 through the holder at the side opposite the portion 98, engages the rod to maintain the holder in any position to which it may be adjusted, either transversely of the machine or angularly about the rod. The first movement permits the finger to be brought more or less closely into alignment with the pen with which it is to co-operate, while the movement about the rod acts to vary the pressure of the finger upon the sheet. The 20 fingers 90, which are associated with the first set of pens, their forward ends lying just at the rear of these, are preferably of substantial width, being of sheet metal. These contact with a considerable width of 25 the sheet lateral, and are especially adapted for use with multiple pens used for ruling closely placed lines, as is illustrated at 104. The fingers 92 are of a different character from those numbered 90, being narrower and formed of rather slender round wire. This is because when the sheets have 30 reached the second set of pens with which these fingers co-operate, they have upon their surfaces lines of wet ink ruled by the 35 first pen-set, with which the fingers 92 must be arranged out of contact. In either case, these fingers force the elevated portions of the sheets down into parallelism with the conveyor 18 and in alignment with the general surfaces of the sheets, so that the pens 40 will strike accurately in accordance with their settings.

I claim:

1. In a ruling machine, a plurality of 45 sets of movable ruling devices, actuating mechanism for each set of ruling devices, driving means, and positive continuously acting connections from the driving means to each actuating mechanism, each of said 50 connections being individual to an actuating mechanism.

2. In a ruling machine, a plurality of 55 sets of movable ruling devices, actuating mechanism for each set of ruling devices, driving means, continuously acting connections from the driving means to each actuating mechanism, each of said connections being individual to an actuating mechanism, and means included in the connections for 60 varying the action of the actuating mechanism.

3. In a ruling machine, a plurality of 65 sets of movable ruling devices, mechanism including rotatable actuating means for each set of ruling devices, driving means,

connections from the driving means to each actuating mechanism, each of said connections being individual to an actuating mechanism, and means included in the connections between the driving mechanism and 70 each actuating mechanism for varying the action of such actuating mechanisms.

4. In a ruling machine, a plurality of 75 ruling devices, a movable work-controlling device co-operating with each ruling device, actuating mechanism for each work-controlling device, driving means, and connections from the driving means to each actuating mechanism, each of said connections being individual to an actuating mech- 80 anism.

5. In a ruling machine, a plurality of 85 movable ruling devices, a movable work-controlling device co-operating with each 90 ruling device, actuating mechanism for each ruling device and its work-controlling device, driving means, and connections from the driving means to each actuating mechanism, each of said connections being individual to an actuating mechanism.

6. In a ruling machine, a plurality of sets 95 of ruling devices, actuating mechanism for each set of ruling devices, means for advancing work to each set of ruling devices, driving means, and connections from the driving means to each advancing means, each of said connections being individual to an advancing means.

7. In a ruling machine, a plurality of 100 ruling devices, actuating mechanism for each ruling device, means for advancing work to each ruling device, driving means, connections from the driving means to each advancing means, each of said connections being individual to an advancing means, 105 and means included in the connections for varying the action of the advancing means.

8. In a ruling machine, a plurality of 110 ruling devices, actuating mechanism for each ruling device, means for advancing work to each ruling device, driving means, connections from the driving means to each actuating mechanism independent of the associated actuating mechanism, and connections from the driving means to each advancing means, each of said connections being individual to an advancing means.

9. In a duplex ruling machine, a plurality 115 of ruling apparatus each provided with a movable set of ruling devices, a cam-shaft for actuating each set of ruling devices, a system of power-shafting for establishing driving connection between the plurality of apparatus, and gearing connecting the power-shafting to each cam-shaft.

10. In a duplex ruling machine, a plurality 120 of ruling apparatus each provided with a movable set of pens, a cam-shaft for actuating each set of pens, a system of power-shafting for establishing driving con- 125

- nection between the plurality of apparatus, and change-speed gearing connecting the power-shafting to each cam-shaft.
11. In a duplex ruling machine, a plurality of ruling apparatus each provided with a movable set of pens, a movable gate associated with each set of pens, a cam-shaft for actuating each set of pens and its gate, a system of power-shafting for establishing driving connection between the plurality of apparatus, and gearing connecting the shafting to each cam-shaft.
12. In a duplex ruling machine, a plurality of ruling apparatus each provided with a movable set of pens, a cam-shaft for actuating each set of pens, a conveyor for delivering sheets to each set of pens, a system of power-shafting for establishing driving connection between the plurality of apparatus, gearing connecting the power-shafting to each cam-shaft, and gearing connecting the power-shafting to each conveyor.
13. In a duplex ruling machine, a plurality of ruling apparatus each provided with a movable set of pens, a cam-shaft for actuating each set of pens, a conveyor for delivering sheets to each set of pens, a system of power-shafting for establishing driving connection between the plurality of apparatus, gearing connecting the power-shafting to each cam-shaft, and gearing connecting the power-shafting to each conveyor, the gearing of one conveyor being arranged for change to vary the travel of said conveyor.
14. In a duplex ruling machine, associated supporting means, driving means movable in each supporting means, connections between the driving means, motor means joined to one of the driving means, a set of ruling devices movable upon each supporting means, a cam device for actuating each set of ruling devices, and a train of gearing connecting each driving means to a cam-device.
15. In a duplex ruling machine, associated frames, a driving shaft journaled in each frame, gearing connecting the shafts, motor means joined to one of the shafts, a set of pens movable upon each frame, a cam-shaft for actuating each set of pens, and a train of change-speed gearing connecting each driving shaft to a cam-shaft.
16. In a duplex ruling machine, associated frames, a driving shaft journaled in each frame, gearing connecting the shafts, motor means joined to one of the shafts, a set of ruling devices movable upon each frame, a cam-shaft for actuating each set of ruling devices, a conveyor for delivering sheets to each set of pens, a train of gearing connecting each driving shaft to a cam-shaft, and a train of gearing connecting each driving shaft to a conveyor.
17. In a duplex ruling machine, associated frames, a driving shaft journaled in each frame, gearing connecting the shafts, motor means joined to one of the shafts, a set of pens movable upon each frame, a cam-shaft for actuating each set of pens, a conveyor for delivering sheets to each set of pens, a train of gearing connecting each driving shaft to a cam-shaft, and a train of gearing connecting each driving shaft to a conveyor.
18. In a duplex ruling machine, a plurality of ruling apparatus including sets of movable ruling devices, actuating mechanism for each set of ruling devices, transfer mechanism between the plural ruling apparatus, driving means, separate connections from the driving means to the actuating mechanisms, and connections to an actuating mechanism for operating the transfer mechanism.
19. In a duplex ruling machine, a plurality of ruling apparatus including sets of movable ruling devices, a cam-shaft for actuating each set of ruling devices, transfer mechanism between the plural ruling apparatus, a driving shaft, separate gearing connecting the driving shaft to each cam-shaft, and gearing to a cam-shaft for operating the transfer mechanism.
20. In a duplex ruling machine, a plurality of ruling apparatus including sets of movable pens, a cam-shaft for actuating each set of pens, transfer mechanism between the plural ruling apparatus, a driving shaft, change-speed gearing connecting the driving shaft to each cam-shaft, and gearing to a cam-shaft for operating the transfer mechanism.
21. The combination with a ruling apparatus having means acting upon the sheets to be ruled and including ruling devices, of mechanism having a plurality of means for feeding work toward the ruling devices, and separate means for establishing driving connections from the ruling apparatus to the respective feeding means.
22. In a ruling machine, movable ruling devices, actuating mechanism organized to control the ruling effect of the device, feeding mechanism arranged to deliver sheets from a pile to the ruling devices, and driving connections between the actuating mechanism and feeding mechanism.
23. In a ruling machine, movable ruling devices, actuating mechanism organized to control the contact of the device with the sheets to be ruled, feeding mechanism arranged to deliver sheets from a pile to the ruling devices and having means to engage and advance sheets from the pile, and driving connections between the actuating mechanism and advancing means.
24. The combination with a ruling apparatus having movable ruling devices, actuating mechanism therefor and means for ad-

- vancing sheets to be ruled to the ruling devices, of mechanism provided with a plurality of means for feeding sheets toward the advancing means, driving connections for 5 the advancing means to one of the feeding means, and driving connections from the actuating mechanism to another of the feeding means.
25. The combination with a ruling apparatus having movable ruling devices, actuating mechanism therefor and means for advancing sheets to be ruled to the ruling devices, of feeding mechanism having means arranged to engage and deliver sheets from 10 a pile and means arranged to receive sheets from such delivering means and advance them to the advancing means of the ruling apparatus, driving connections between the advancing means of the ruling apparatus 15 and that of the feeding mechanism, and driving connections between the actuating mechanism of the ruling apparatus and the delivering means of the feeding mechanism.
26. In a ruling machine, a plurality of 20 ruling devices, a movable work-controlling device co-operating with each ruling device, actuating mechanism for each work-controlling device, driving means, connections from the driving means to each actuating mechanism independent of the associated actuating mechanism, mechanism arranged to feed 25 sheets from a pile toward one of the ruling devices, and connections from the actuating mechanism of such ruling device to the feeding mechanism.
27. In a ruling machine, a movable ruling device, a cam-shaft for actuating the ruling device, feeding mechanism arranged to deliver sheets from a pile toward the ruling apparatus, and gearing for driving the feeding mechanism from the cam-shaft.
28. In a ruling machine, a movable ruling pen, a cam-shaft for actuating the pen, a movable fanning and feeding device for co-operating with a pile of sheets, and gearing connecting the cam-shaft and fanning and feeding device.
29. In a ruling machine, a movable ruling pen, a cam-shaft for actuating the pen, a conveyor for advancing sheets beneath the pen, a movable fanning and feeding device for co-operation with a pile of sheets, a conveyor receiving sheets fed by the fanning and feeding device and delivering them to the conveyor at the pen, gearing connecting the cam-shaft and fanning and feeding device, and gearing connecting the conveyors.
30. In a duplex ruling machine, a plurality of ruling apparatus each provided with a movable set of pens, a cam-shaft for actuating each set of pens, a system of power-shafting for establishing driving connection between the plurality of apparatus, gearing connecting the power-shafting to each cam-shaft, a movable fanning and feeding device for advancing sheets from a pile toward one of the ruling apparatus, and gearing connecting the cam-shaft of such apparatus with the fanning and feeding device.
31. In a ruling machine, the combination 70 with a ruling device, of means arranged to move work in engagement with the ruling device, and a yieldable pressure member contacting with the moving work at the rear of and adjacent to the ruling device.
32. In a ruling machine, the combination 75 with a ruling device, of means arranged to move work in engagement with the ruling device, a yieldable pressure member contacting with the moving work at the rear of and adjacent to the ruling device, and means arranged to permit the position of the pressure member to be varied.
33. In a ruling machine, the combination 80 with a ruling device, of means arranged to move work in engagement with the ruling device, a yieldable pressure member contacting with the moving work at the rear of and adjacent to the ruling device, and means arranged to permit the degree of pressure of 85 the member upon the work to be varied.
34. In a ruling machine, the combination 90 with a ruling device, of a stationary support situated adjacent thereto, and a pressure member variable in position upon the support and contacting with the work in proximity to the ruling device.
35. In a ruling machine, the combination 95 with a set of ruling pens and a conveyor for moving sheets to be ruled in engagement 100 with the pens, of a rod extending adjacent to the set of pens, and a finger mounted upon the rod for cooperation with the conveyor.
36. In a ruling machine, the combination 105 with a set of ruling pens and a conveyor for moving sheets to be ruled in engagement with the pens, of a rod extending adjacent to the set of pens, a holder adjustable upon the rod, and a finger carried by the holder 110 for co-operation with the conveyor.
37. In a ruling machine, the combination 115 with a set of ruling pens and a conveyor for moving sheets to be ruled in engagement with the pens, of a cylindrical rod extending adjacent to the set of pens, a holder formed to turn upon the rod, a set-screw threaded through the holder and engaging the rod, and a spring-finger carried by the holder.
38. In a ruling machine, a plurality of 120 sets of ruling devices, means for advancing sheets successively to the sets of ruling devices, and members for contact with the sheets co-operating with the advancing means adjacent to each set of ruling devices, such members at the different sets of ruling devices being constructed and arranged to produce different effects upon the sheets.
39. In a ruling machine, a plurality of 125 sets of pens, a conveyor presenting sheets 130

successively to the action of the sets, spring-fingers of substantial width co-operating with the conveyor adjacent to the set of pens to which the sheets are first presented, and 5 more narrow spring-fingers co-operating with the conveyor adjacent to a succeeding set.

40. In a ruling machine, a plurality of sets of pens, a conveyor presenting sheets successively to the action of the sets, spring-fingers of substantial width co-operating with

the conveyor adjacent to the set of pens to which the sheets are first presented, more narrow spring-fingers co-operating with the conveyor adjacent to a succeeding set, and 15 means arranged to permit the fingers to be adjusted longitudinally of the sets of pens and toward and from the conveyor.

Signed at Boston, in the county of Suffolk and State of Massachusetts, this first day 20 of August, 1923.

HARMON E. LINDBLADH.
